SECONDARY CLOCK SYNCHRONIZING MECHANISM

**Reynold B. Johnson and Edward F. Geiger, Bing-
hamton, N. Y., assignors to International Busi-
ness Machines Corporation, New York, N. Y.,
a corporation of New York**

Application April 25, 1946, Serial No. 664,933

16 Claims. (Cl. 58—26)

1

This invention relates to time-keeping apparatus and more particularly to secondary clocks and similar time-keeping units of the type normally driven by individual driving motors, for example, a synchronous A. C. motor, and, which are automatically regulated at selected intervals in response to time signals transmitted from a source of correct or standard time.

An object of the invention is to provide secondary time-keeping apparatus of the type referred to which is of improved construction and arrangement of parts.

A further object is to provide a novel form of secondary clock construction which includes an improved structural combination and arrangement of parts for advancing the clock, when slow, to a chronological position coincident with standard time.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a transverse vertical sectional view through a secondary clock constructed in accordance with the present invention, the outline of the face and hands of the clock being shown by dot-and-dash lines, and the plane of the section being indicated by the line (—) of Fig. 2;

Fig. 2 is a vertical longitudinal sectional view taken on the line 2—2 of Fig. 1, with the clock operating mechanism appearing in vertical elevation:

Fig. 3 is a vertical elevational view of the clock mechanism and showing the side thereof opposite to that shown in Fig. 2;

Fig. 4 is a transverse vertical sectional view through the clock mechanism taken on the line 4—4 of Fig. 2;

Fig. 5 is a detail elevational view showing the rear face of the clock gear which drives the minutes hand;

Fig. 6 is an enlarged plan sectional view of the clock mechanism taken on the line 6—6 of Fig. 1;

Fig. 7 is an enlarged detail perspective view showing the operative relationship between the seconds and minutes stop pawls with respect to the seconds stop arm and the minutes stop stud, certain parts of the clock mechanism not forming a direct part of this relationship being omitted for the purposes of clarity;

Fig. 8 is a fragmentary transverse vertical sec-

tional view of the clock mechanism taken on the line 8-8 of Fig. 2;

Fig. 9 is a detail elevational view showing the time-correcting disk with related parts attached thereto;

Figs. 10 to 13 inclusive are fragmentary vertical sectional views of the clock mechanism each being taken on the same plane as Fig. 1, and the views showing the different relative positions occupied by the parts during the several operating steps of a time-correcting operation.

15 Referring now in detail to the construction illustrated, the reference numeral 10 indicates, in its entirety, one preferred form of an automatically regulated secondary clock constructed in accordance with the present invention. As shown, the clock 10 comprises the usual face plate 11, seconds hand 12, minutes hand 13, and hours hand 14. Parallel front and rear support plates 20 of the clock are indicated at 15 and 16, respectively, and they are suitably secured in their predetermined spaced relationship by pillars 17. An electric driving motor for the clock is indicated by the character 18, and is shown as being supported by the rear plate 16. The remaining operating mechanisms of the clock are mounted between the plates 15 and 16, as will presently appear.

The motor 18 is preferably of the self-starting synchronous type and is adapted to be driven at its designed time rate from the available frequency-regulated A. C. light and power line. The output shaft 20 of the motor is operatively connected by a pinion 21 to a seconds driving gear 22 which is rotatably mounted on a seconds shaft 23. With the motor operating from the available A. C. power line, the seconds gear 22 will be driven at the rate of one R. P. M.

The seconds shaft 23 is rotatably supported at its rear end by the rear support plate 16 and is rotatably supported at its forward end in a minutes sleeve 24, the latter being in turn journalled in an hours sleeve 25 which is rotatably supported within a bearing opening in the front support plate 15. The seconds shaft 23 is rotated from the seconds gear 22 through a suitable friction drive connection indicated at 26. This operative connection is made through a seconds driving pinion 27 which is rotatively mounted on the shaft 23 and is fixed to the rear face of the seconds gear 22. The pinion 27 is connected by the friction connection 26 with a collar 28 fixed to the seconds shaft 23. As will be apparent from an examination of Figs. 2, 3, and 6, the connection 26 comprises a spider-like spring member hav-

ing a base element fixed to the rearward face of the driving pinion 21 and having spring fingers extending outwardly and rearwardly therefrom and frictionally engaging the forward face of the collar 28. Thus, normally the seconds gear 22 and the seconds shaft 23 both operate at their regular speed of one R. P. M. However, the friction drive connection 26 permits relative movement between the seconds gear 22 and seconds shaft 23 when required for time correcting operations, as will later appear.

Formed as an integral part of the collar 28 is an outwardly extending seconds stop arm 29. The seconds hand 12 is connected to the opposite or forward end of the seconds shaft 23. Thus, the stop arm 29 and hand 12 move together with the seconds shaft 23 and the arm 29, therefore, occupies a definite angular position with respect to the hand 12 for any given time indicating position of the latter. It is noted that in Figs. 1, 3, 6, 7, 8, 10, and 11, the stop arm 29 is shown in the angular position it occupies when the seconds hand 12 indicates fifty-five seconds after the even minute. Fig. 12 shows the position of the arm 29 when the seconds hand 12 is at the even minute position which may also be referred to as the zero or sixtieth second position.

The seconds driving pinion 21 is in mesh with gear 31 which has a suitable friction driving connection 32 with a concentric hub 33 fixed to a shaft 34, the latter being journaled at its two ends in the two clock support plates 15 and 16, respectively, and being arranged in spaced parallel relation with respect to the seconds shaft 23 and minutes sleeve 24. A pinion 35 is also fixed to the shaft 34 and meshes with a minutes drive gear 36 fixed to the minutes sleeve 24. Fig. 5 shows the gear 36 apart from other elements of the clock. As shown, the minutes indicating hand 13 is secured to the forward end of the minutes sleeve 24. The gears 21, 31, 35, and 36 are designed to provide for the driving of the minutes sleeve 24 at its correct time rate of one R. P. H. from the seconds gear 22 and motor 18. The friction driving connection 32 between the gear 31 and hub 33 permits relative motion between the constantly rotating seconds gear 22 and the minutes gear 36 and minutes hand 13 when necessary during time correcting periods, as will presently appear.

Projecting from the forward side of the minutes gear 36, is a minutes stop stud 37 which occupies a definite angular position for each time-indicating position of the minutes hand 13 (see Figs. 1, 3, 5, 6, 7). Also fixed to the minutes gear 36 and on the rear face thereof, is a spring finger 38. As shown, the finger 38 is fixed at one end thereof to the gear by suitable pins 39 and the remaining portions of the spring element project away from the rear face of the gear and are normally held in such position by the inherent spring force in the finger 38. The finger 38 terminates at its outer or free end in an outer abutment edge or face 41. The purpose of the spring finger 38 will be described in detail hereinafter. The minutes stop stud 37 and the finger 38 are shown in Figs. 1, 4, 5, 6, 7, 10, 11, and 12 in the position they occupy when the minutes hand 13 indicates fifty minutes past the even hour. In Fig. 13, the stud 37 and finger 38 are shown in the position they occupy at the even hour position, which may also be referred to as the zero or sixtieth minute position.

The hours sleeve 25, which, as stated, is journaled on the minutes sleeve 24, is driven from

the latter at its proper time rate through the conventional gear reduction train composed of the gears 42, 43, 44, and 45 (see Figs. 2, 3, 4, and 6). As shown, the hours hand 14 is secured to the forward end of the hours sleeve 25.

A time-correcting disk 46 is rotatably mounted on the seconds shaft 23 at the rear of the minutes gear 36 and is kept in axially spaced relation with respect to the latter by a forwardly extending hub 47 (see particularly Figs. 6 and 9). The time-correcting disk 46 is normally held against rotation at a predetermined angular position thereof by means of an upper hooked end 48 of a pivoted stop pawl 49 (Fig. 1) engaging a tail portion 51 of an advancing pawl 52, the latter being pivoted on the disk 46 by a suitable pin 53 projecting from the rear side of the disk and adjacent the periphery thereof. The stop pawl 49 is pivoted on a fixed rod 54 supported at its ends by the front and rear plates 15 and 16, respectively. When the hook 48 engages the tail 51 as shown in Figs. 1 and 10, the disk 46 is thus held against rotation in the predetermined normal angular position referred to. A tension spring 64 connecting a depending arm 65 of the stop pawl 49 and a fixed rod 66 carried by the plates 15 and 16, constantly urges the pawl 49 clockwise as viewed in Fig. 1 and thereby holds the hook 48 and tail 51 of the dog 52 in engagement at the predetermined normal angular position of the disk 46.

The disk 46 is further retained in its said normal angular position by a stop-actuating and detent lever 55 which includes a depending arm 56 having a wedge-shaped lower end 57 fitting within a correspondingly shaped notch 58 in the periphery of the disk when the disk is in its said predetermined normal position. The stop actuating lever 55 is fixed on a shaft 59 which is journaled at its ends in the support plates 15 and 16 (see Figs. 6 and 7). A tension spring 61 connecting an upwardly extending arm 62 of the stop lever 55 and a fixed rod 63 held at its ends by the plates 15 and 16, constantly urges the wedge-shaped lower end 57 against the periphery of the disk 46 and thereby holds such end 57 within the notch 58 and retains the disk in its predetermined normal position.

Projecting from the forward face of the disk 46 and into the path of the outer edge 41 of the spring finger 38, which is carried by the minutes gear 36, is a clock advancing stud 67. The stud 67 and spring finger 38 comprises the two coacting parts of a one-way coupling between the minutes gear 36 and the time-correcting disk 46. During normal time-keeping operation when the disk 46, and likewise its stud 67 remain stationary and the minutes gear 36 and spring finger 38 are moved clockwise at the regular time rate of one R. P. H., as previously described, the advancing stud 67 will not interfere with such normal time-keeping movement of the clock gear 36. During such movement, the outer, or rear, face of the finger 38, at points spaced inwardly from the outer edge 41 thereof, will first engage the outer end of the stud 67; and, as the gear 36 continues to move clockwise, the outer face of the finger will simply wipe or slide, over the end of stud 67 which will only result in the outer portions of the finger being moved inwardly against its inherent spring force and toward the face of the gear 36 and consequently the normal clockwise movement of the gear will not be retarded. When the outer free edge 41 of the finger 38 clears the stud 67, the finger will then snap outwardly from

the face of the gear 36 and back to its normal position. However, as will appear more fully hereinafter, the disk 46 is released periodically to effect a time-correcting operation and the disk then rotates clockwise at a rate materially faster than the normal rate of the minutes gear. The stud 67 may then overtake and engage the edge 41 of the spring 38 and thereby advance the gear 36 at the speed of the disk 46.

A biasing spring 68 (see Fig. 9) has one end thereof engaging the pawl 52 and is fixed at its other end to the time-correcting disk 46, the purpose of the spring 68 being to constantly urge the advancing pawl 52 to move in a clockwise direction, as viewed in Figs. 1, 9, and 10. Thus, when the stop pawl 49 is moved counterclockwise, in a manner which will be presently explained, to release its upper hooked end 48 from the tail portion 51 of the advancing pawl 52, the spring 68 will move the pawl 52 about its pivot 53 and thereby effect locking or clutching engagement of its outer hooked end 69 with the teeth of a ratchet wheel 70. The ratchet wheel 70 is rotatably mounted on the seconds shaft 23 and is fixed to the forward side of the seconds gear 22 and rotates constantly therewith so that when the advancing pawl 52 is released by outward movement of the stop pawl 49, and the advancing pawl 52 thus engages the ratchet 70, the disk 46 is clutched to the ratchet 70 and is rotated thereby at the speed of the seconds gear 22. As will appear more fully hereinafter, after the stop pawl 49 is moved counterclockwise to release the advancing pawl 52 and the disk 46, the spring 64 will return the stop pawl to the position shown in Figs. 1, 10, 12, and 13, at which time its hooked end 48 will be in the path of the tail 51 of the pawl 52 and so that it will be engaged by the tail 51 as the disk 46 completes one revolution. This engagement of the tail 51 and hooked end 48 will result in the pawl 52 being pivoted counterclockwise (as viewed in Fig. 1) against the force of its biasing spring 68 and thereby disengaging the advancing pawl 52 from the teeth of the ratchet wheel 70 and stopping the disk 46 at its said predetermined normal angular position. The pawl 52, ratchet 70, and pawl 49 may be considered as elements of a one-revolution clutch which provides a driving connection between the driving gear 22 and the time-correcting disk 46. As stated previously, the wedge-shaped end 57 fits fully within the notch 58 at the normal angular position of the disk 46 and thereby aids in holding the disk at such position.

A stop pawl 72 is rotatably mounted on the shaft 59 and in substantially the same transverse plane as the previously described stop arm 29 which is fixed to the seconds shaft, and a second stop pawl 73 (see Figs. 4, 6, and 7) is rotatably mounted on the shaft 59 in substantially the same plane as the path of movement of the stop stud 37 on the minutes gear 36. Associated with and mounted alongside the stop pawl 72 is a control arm 74 fixed to the shaft 59, and associated with the stop pawl 73 is a second control arm 75 which is also fixed to the shaft 59. The arm 74 is provided with a lug 76 extending under its associated pawl 72 and a tension spring 77 connecting the arm 74 and a tail 78 on the pawl 72 constantly urges the pawl 72 against the lug 76 so that the pawl 72 and associated control arm 74 normally move together as a unit with the rotation of the shaft 59. Likewise, the arm 75 is provided with a lug 79 and a tension spring 80 functions to yieldingly hold the arm 75 and its

associated pawl 73 so that they also normally move together as a unit.

With the stop actuating lever 55 in its normal position occupied in Figs. 1, 4, 7, 10, 11, and 13 where the end 57 thereof is in the positioning notch 58, the stop pawls 72 and 73 occupy positions which are out of the paths of movement of the arm 29 and stud 37, respectively. When the time-correcting disk 46 moves from its predetermined normal position, the wedge-shaped end 57 is cammed out of the notch 58 and onto the periphery of the disk 46 (see Figs. 7 and 8). This will result in the shaft 59 and arms 74 and 75 being moved counterclockwise as viewed in Figs. 1, 6, 7, 8 and 10 to 13 inclusive, and clockwise as viewed in Fig. 4. The springs 77 and 80 will cause the stop pawls 72 and 73 to move with their associated arms 74 and 75, respectively, and to positions where the pawl 72 lies in the path of movement of the outer end of the arm 29 and the pawl 73 lies in the path of movement of the stop stud 37. The construction is such that when the pawl 72 is thus moved into an intercepting or blocking position with respect to the arm 29 and when the latter engages the pawl, the arm 29 and seconds shaft 23, will be stopped at the even minute or sixtieth second position of the seconds hand 12. The friction connection 26 permits continued movement of the seconds gear 22 when the arm 29 is thus held by the pawl 72. Also, the other pawl 73 is so arranged that when it is in its intercepting or blocking position, it will stop the stud 37 and minutes gear 36 at the position where the minutes hand 13 indicates the even hour, or which, as stated, may also be referred to as the zero or sixtieth minute position of the hand 13. The friction connection 32 between the gear 31 and hub 33 permits stopping of the minutes gear and minutes hand without affecting movement of the seconds gear 22.

The spring connections between the stop pawls 72 and 73 and their associated arms 74 and 75 serve to prevent damage to the parts in case the stop pawls should be actuated when either the arm 29, or stud 37, occupies a position where it would be struck by its related pawl. Thus, if either stop pawl 72 and 73 strikes and is thereby stopped by its associated arm 29, or stud 37, as such pawl is actuated, its tension spring 77, or 80, will permit continued movement of its associated arm 74, or 75, and thereby prevent damage to the parts. When the latter occurs and the arm 29, or stud 37, moves out of engagement with its pawl, the associated tension spring will then move such pawl into its intercepting position.

According to the illustrative embodiment, means is provided for automatically correcting the time setting of the secondary clock at a preselected hourly time position of a master clock or other source of standard time. The correction may be effected each hour, or during certain selected hours, if desired. As the frequency of the available alternating current is closely regulated at the source, synchronous motor driven clocks will seldom vary more than a small fraction of a minute, unless there be an interruption in the power supply or the existence in the secondary clock of an unusual amount of friction or binding of the working parts, such as would cause the clock to lose time. As will presently appear, the illustrative embodiment will automatically correct for loss of time up to 59

minutes and will correct for gain of time for a fraction of a minute.

Automatic correction is effected each hour in the illustrative embodiment, by releasing the time-correcting disk 46 at fifty-nine minutes past the hour according to standard time. As stated previously, as soon as the advancing pawl 52 engages the ratchet 70 and the disk 46 thereby begins to move, the lower wedge-shaped end 57 of the lever 55 is cammed out of its notch 58 and the stop pawls 72 and 73 are thereby moved, respectively, into intercepting or blocking positions with respect to the seconds stop arm 29 and the minutes stop stud 37. Thus, the pawls 72 and 73 are moved into their intercepting positions substantially simultaneously with the releasing of the disk 46.

The disk 46 is released at the fifty-ninth minute past each hour by a trigger mechanism indicated generally by the reference character 82 (see Figs. 1, 4, and 10 to 13 inclusive) and which is operated to release the disk under the control of a trip magnet 83 which is suitably supported by the plates 15 and 16. The energizing of the magnet 83 cocks the trigger mechanism and the deenergizing of the magnet trips the mechanism to release the disk at the fifty-ninth minute.

As shown in Figs. 1, 3, 4, 6, and 10 to 13 inclusive, the trigger mechanism 82 includes the armature 84 of the magnet 83 which is pivoted on a fixed rod 85 carried by the support plates 15 and 16, a laterally movable trip pawl 86 pivoted by a pin 87 to an upwardly extending arm 88 of the armature 84, and the pivoted stop pawl 49 having a depending latch plate 89 adapted to coact with a latching notch 90 formed in the upper left-hand part, as viewed in Fig. 1, of the trip pawl 86. A tension spring 92 connecting the right-hand end of the pawl 86 and one of the pillars 17, constantly urges the trip pawl towards the right and thereby also urges the armature 84 in a clockwise direction towards its deenergized position. A fixed stop rod 93 extending between the support plates 15 and 16 coacts with an upwardly extending hook portion 94 on the pawl 86 to limit its movement towards the right and also coacts with a depending tail portion 95 on the stop pawl 49 to limit clockwise movement of the latter under the force of the tension spring 64. A tension spring 96 connecting the left-hand end of the trip pawl 86 and the fixed rod 66 urges the trip pawl 86 upward against the stop rod 93.

Time-correcting operation

A time-correcting operation will be readily understood from a study of Figs. 1, 4, and 10 to 13 inclusive of the drawings. In Fig. 1, the parts are shown in the relative positions normally occupied between time-correcting signals. As shown, the time indicated by the clock 10 in Fig. 1 is ten minutes and five seconds before 2 o'clock. For the purposes of description, it will be assumed that an electrical time signal or impulse is received by the magnet 83 from a master clock, not shown, or other source of standard time. It will also be assumed that the transmission of the impulse will begin a moment before the fifty-ninth minute of the standard time source, for example, one or two seconds, and that the impulse will terminate at the fifty-ninth minute, and that the secondary clock 10 is now running slow with respect to standard time by the amount indicated in Fig. 1. The impulse will energize the magnet 83 and the latter will attract its ar-

mature 84 and move the parts of the trigger mechanism from the position shown in Fig. 1 to their cocked position which is the position shown in Fig. 10. As the armature 84 is attracted it moves counterclockwise and moves therewith the trip pawl 86 towards the left and against the force of the tension spring 92. This will move the latching notch 90 beneath the lower edge of the latch plate 89 and during such movement the left-hand end of the trip pawl will also be moved upward due to the force of the spring 96 and as permitted by the cam face 97 on the pawl 86 engaging the stop rod 93 and until the lower end of the latching plate 89 is in the latching notch 90.

As stated, the standard time signal, or impulse, terminates at the fifty-ninth minute of the master clock or other source of correct time, and thereby deenergizes the trip magnet 83 which permits the spring 92 to actuate the trigger mechanism and thereby release the time-correcting disk. This trigger actuating operation can best be understood with reference to Fig. 11 which shows the relative position of the parts at the moment the disk 46 is released. As the magnet 83 becomes deenergized, the spring 92 pulls the trip pawl 86 towards the right. As the lower end of the latch plate 89 is engaged by the left-hand end of the latching notch 90, the plate 89 and stop pawl 49 will be moved counterclockwise by the spring 92 and to a position where the upper hooked end 48 thereof will release the advancing pawl 52 so that the latter will engage the ratchet 70 under the force of the spring 68, as explained previously. As the spring 92 continues to move the trip pawl 86 towards the right, the cam surface 97 which is in engagement with the stop rod 93, cams the left-hand end of the pawl 86 downward to a point where the latching notch 90 releases the lower edge of the latch plate 89 and thereby permits the spring 64 to restore the stop pawl 49 to its normal position shown in Figs. 1, 10, 12, and 13. By the time the stop pawl 49 is thus restored to its normal position, the disk 46 will have carried the tail 51 of the advancing pawl 52 clockwise beyond its upper hooked end 48, so that the latter will come to rest in a position to intercept and be engaged by the tail 51 as the disk 46 completes a revolution and will thereby disengage the pawl 52 and ratchet 70 and stop the disk 46 at the end of its revolution. Fig. 13 shows the relative position of the parts at the end of the revolution of the time-correcting disk.

As the time indicated by the secondary clock in Fig. 1 is ten minutes and five seconds before two o'clock and as the assumed standard time is the fifty-ninth minute at the moment of releasing of the disk 46, the time-correcting disk during its minute of rotation, the sixtieth minute, advances the time setting of the clock to two o'clock and releases the clock for normal operation exactly at the end of the sixtieth minute, with the result that the time indicated by the secondary clock will then be coincident with the standard time source.

As explained previously, the stop pawls 72 and 73 are moved into their respective intercepting positions as soon as the disk 46 begins to rotate, and also the disk 46 rotates at the speed of the seconds gear 22, thereby requiring one minute to complete its revolution. Thus, with the secondary clock at the time position indicated in Fig. 1, when the disk 46 commences to rotate at the beginning of the sixtieth minute, the stop pawl 72 will immediately move into its blocking position and will stop the arm 29 and

seconds hand 12 when the latter reaches the even minute or sixty-second position. The stop pawl 73 will also immediately move into its intercepting position. As the disk 46 rotates at the speed of the seconds gear 22, the advancing stud 67 carried thereby will move clockwise an angular distance equal to a fraction more than fifty seconds before engaging the outer edge 41 of the spring finger 38 on the minutes gear 36. The parts are shown in Fig. 12 in their relative positions at the moment the stud 67 engages the end of the finger 38. The stud 67 will then rotate the minutes gear 36 and minutes hand 13 clockwise at the same speed as the seconds gear 22 for the remaining portions of the sixtieth minute. As explained, the tail 51 of the advancing pawl 52 strikes the hooked end 48 of the stop pawl 49 at the end of the revolution of the disk 46, and thereby disconnects the disk 46 from the seconds gear 22 and stops the disk 46. Simultaneously therewith, the wedge-shaped end 57 of the lever 55 enters the notch 58 and thereby moves the stop pawls 72 and 73 back to their normal positions so as to release the stop arm 29 and stud 37. The construction is such that the latter occurs exactly at the end of the sixtieth minute so that the hands 12 and 13 will then indicate the correct time as they commence rotating. The relative position of the parts at the moment the disk 46 stops rotating and the arm 29 and stud 37 are released, is shown in Fig. 13.

The foregoing describes the time-correcting operation when the secondary clock is slow with respect to standard time at the fifty-ninth minute. If the secondary clock indicates the correct time at the fifty-ninth minute the relative position of the parts when the disk 46 is released is as follows: the outer edge 41 of the spring 38 will be at a chronological position just one minute short of clearing the forward edge of the advancing stud 67, so that the stud 67 will make its revolution with the disk 46 while the edge 41 is moving an angular distance equal to one minute and will just engage the edge 41 at the end of the sixtieth minute when the disk 46 comes to rest. Also, with the clock indicating correct time at the fifty-ninth minute, the stop arm 29 will be short of the intercepting position of the stop pawl 72 by the angular distance the arm 29 will travel in one second, and the leading face of stop stud 37 will be short of the intercepting position of the stop pawl 73 by the angular distance the stud 37 will travel in one minute. The construction is such that the pawls 72 and 73 will reach their intercepting or blocking positions when the disk 46 has been rotated slightly more than one second. Consequently, when the clock is on time, pawl 72 will move into blocking position just as the seconds stop arm 29 moves underneath the pawl 72 and past the blocking position and the pawl 72 will move out of blocking position and release the arm 29 exactly on the even minute. When the pawl 73 moves into its blocking position the forward face of the minutes stop stud 37 will be short of the pawl 73 by the amount it will travel in approximately fifty-nine seconds, and the pawl 73 moves out of its blocking position to release the minutes stud and gear exactly on the even hour.

From the foregoing, it is apparent that the clock construction disclosed herein will also correct itself when the clock is fast by less than a minute at the moment the standard time signal

is received. This amount of correction for running fast is considered ample in a clock driven by a synchronous motor as the controlled frequency at power stations is always kept within a closer range than one minute. In case the clock is running fast by a fraction of a minute at the moment the signal is received, the stop pawl 73 will intercept and stop the stud 37 upon reaching the even hour position and will release the stud 37 and minutes gear at the even hour, as before explained.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In time-keeping apparatus, the combination of a driving motor adapted to operate continuously at a uniform time rate; a time member mounted for rotation about a given axis; clock-driving means connecting said motor and said time member for normally driving the latter at a uniform time-keeping rate; a clock-advancing member adjacent said time member and being rotatable about the same axis as the latter; a one-way coupling comprising a first coacting part secured to and rotatable with said time member and a second coacting part secured to and rotatable with said clock-advancing member and said coupling parts being movable in approximately the same circular path and being constructed so that said first part may move clockwise past said second part without affecting the condition of relative movement of said members and so that said second part, when moving clockwise at a faster rate than said first part and upon overtaking said first part, engages and drives said first part and time member at the rate of said clock-advancing member; means normally holding said clock-advancing member stationary in a predetermined angular position; signal-responsive means adapted to be operated by a signal transmitted at a predetermined instant with reference to standard time for rendering said holding means inoperative; motion-transmitting means including clutch mechanism also operable under the control of said signal-responsive means for connecting said motor and said clock-advancing member to rotate the latter from its normal angular position throughout one complete revolution, said motion-transmitting means and holding means cooperating after completion of one revolution of the clock-advancing member to disconnect the clock-advancing member from the motor and thus terminate further rotation of the clock-advancing member, said clock-advancing member being operable upon rotation thereof when said time member is at a chronological position later than the standard time position to cause said second coacting part to overtake and engage said first coacting part on the time member to advance the latter to a chronological position coincident with standard time at the moment said motor and clock-advancing member become disengaged at the end of one complete revolution of the latter.
2. In time-keeping apparatus, the combination

of a driving motor adapted to operate continuously at a uniform time rate; a rotatable minutes member; yieldable friction means operatively connecting said motor and minutes member for driving the latter at its normal time-keeping rate of one R. P. H.; a clock-advancing member arranged adjacent to and supported for rotation about the same axis as said minutes member; releasable means normally holding said clock-advancing member stationary and in a predetermined angular position; motion-transmitting means including a one-revolution clutch operable to connect said motor and said clock-advancing member for rotating the latter for one revolution at the rate of one R. P. M. and to disconnect said motor and clock-advancing member upon the latter being restored to its said normal angular position; said holding means normally maintaining said one-revolution clutch inoperative; means responsive to the reception of a signal at a predetermined standard time for releasing said holding means to permit said clutch to become effective; and coupling means between said clock-advancing and minutes members and operable, when said minutes member is at a chronological position slower than standard time and upon operation of said clutch, to drive said minutes member clockwise by said clock-advancing member and at the rate of the latter and for an angular distance sufficient to advance the minutes member to a chronological position coincident with standard time at the end of the single complete revolution of said clock-advancing member.

3. In time-keeping apparatus, the combination of a driving motor adapted to operate continuously at a uniform time rate; a rotatable seconds member; means operatively connecting said seconds member and driving motor for driving the former at its normal time-keeping rate of one R. P. M.; a seconds stop element secured to and rotatable with said seconds member; a rotatable minutes member; means operatively connecting said minutes member and driving motor for driving the former at its normal time-keeping rate of one R. P. H.; a clock-advancing member arranged adjacent to and supported for rotation about the same axis as said minutes member; releasable means normally holding said clock-advancing member stationary in a predetermined angular position; motion-transmitting means including a one-revolution clutch operable to connect said motor and said clock-advancing member for rotating the latter through one complete revolution at the rate of one R. P. M. and to disconnect said motor and clock-advancing member upon the latter being restored to its said normal angular position; said releasable holding means also normally maintaining said clutch inoperative; means responsive to the reception of a signal at a predetermined standard time for releasing said holding means to render said clutch operative; coupling means between said clock-advancing and minutes members and operable, when said minutes member is at a chronological position slower than standard time and upon operation of said clutch, for driving said minutes member clockwise by said clock-advancing member and at the rate of the latter and for an angular distance sufficient to advance the minutes member to a chronological position coincident with standard time at the end of the revolution of said clock-advancing member; and stop means movable when said clock-advancing member is moving away from

its said normal angular position into blocking position with respect to said seconds stop element so that it engages and stops the latter together with said seconds member at a predetermined chronological position, said stop means being operable upon a return of said clock-advancing member to its said normal angular position to release said seconds stop element for normal time-keeping movement.

4. In time-keeping apparatus, the combination of a driving motor adapted to operate continuously at a uniform time rate; a rotatable minutes member; clock driving means for rotating said minutes member at its normal time-keeping rate of one R. P. H.; a clock-advancing member adjacent to and supported for rotation about the same axis as said minutes member; releasable means normally holding said clock-advancing member stationary in a predetermined angular position; motion-transmitting means including a one-revolution clutch operable to connect said motor and said clock-advancing member for rotating the latter through one complete revolution at the rate of one R. P. M. and to disconnect said motor and clock-advancing member upon the latter being restored to its said normal angular position; said releasable holding means also normally maintaining said clutch inoperative; means responsive to the reception of a signal at a predetermined standard time for releasing said holding means to render said clutch inoperative; and one-way coupling means between said minutes and clock-advancing members permitting the normal time-keeping movement of said minutes member while said clock-advancing member occupies its said normal angular position and providing, when said minutes member occupies a chronological position later than standard time and upon operation of said clutch, for driving said minutes member by said clock-advancing member clockwise at the rate of the latter and for an angular distance sufficient to advance the minutes member to a chronological position coincident with standard time at the end of one complete revolution of said clock-advancing member.

5. Time-keeping apparatus comprising in combination a motor operable at a uniform time rate; a rotatable minutes member; an abutment element eccentrically mounted thereon and capable of occupying chronological positions with respect to an axis passing through the axis of rotation of the minutes member; means for driving said minutes member from said motor at its normal time rate of one R. P. H.; a clock-advancing member disposed adjacent to and supported for rotation about the same axis as said minutes member; releasable means normally holding said clock-advancing member stationary in a predetermined angular position; motion-transmitting means including a driving member operated by said motor and a clutch mechanism operable to connect said driving member and said clock-advancing member to rotate the latter at the rate of one R. P. M. from its normal angular position and to disconnect said driving member and clock-advancing member at the end of one complete revolution and hold the latter at its said normal angular position; means responsive to reception of a signal at a predetermined standard time for releasing said holding means to render said clutch operative; and an advancing element fixed to said clock-advancing member and operable upon operation of said clutch mechanism when the minutes member is at a chrono-

logical position later than standard time, to overtake and engage the abutment element on said minutes member and to thereby move the minutes member at the rate of the clock-advancing member an angular distance sufficient to advance the minutes member to a chronological position coincident with standard time at the completion of the complete revolution of said clock-advancing member.

6. In time-keeping apparatus, the combination of a driving motor operable at a uniform time rate; a rotatable seconds member; a rotatable minutes member; driving means normally connecting said motor and seconds member for rotating the latter at its normal time-keeping rate; driving means connecting said seconds and minutes members for rotating the latter at its normal time-keeping rate; a seconds stop element secured to and rotatable with the seconds member; a clock-advancing member mounted for rotation about the same axis as said minutes member and positioned alongside thereof in close proximity thereto; releasable means normally holding said clock-advancing member stationary in a predetermined angular position; a one-way coupling comprising a first coacting part secured to and rotatable with the minutes member and a second coacting part secured to and rotatable with said clock-advancing member; said coupling parts being movable in substantially the same circular path and being so constructed that said first part may move clockwise at its normal time-keeping rate past said second part without affecting the condition of relative movement of said minutes member and clock-advancing member and so that said second part, when moving clockwise at a faster rate than said first part and upon overtaking the latter, engages and drives said first part and minutes member at the speed of said clock-advancing member; signal-responsive means adapted to be operated by a signal transmitted at a predetermined instant with reference to standard time for rendering said holding means inoperative; motion-transmitting means including clutch means responsive to the reception of a signal at a predetermined instant with respect to standard time and operable to provide a driving connection between said motor and said clock-advancing member so as to rotate the latter from its normal angular position for a predetermined angular distance and then being effective to disconnect said motor and clock-advancing member, said motion-transmitting means being operable to rotate the clock-advancing member for the predetermined angular distance at a rate sufficient, when the minutes member is slow with respect to standard time, to effect driving engagement of said second and first coupling part and to advance the minutes member to a chronological position coincident with standard time at the moment said clutch means disconnects the clock-advancing member and motor; a stop member; means operable upon engagement of said clutch to move said stop member into a blocking position with respect to said seconds stop element and operable simultaneously with the disconnecting of said clutch to move said stop member out of blocking position to thereby release said seconds stop element and consequently the seconds member for normal time-keeping movement.

7. In time-keeping apparatus, the combination of a driving motor adapted to operate continuously at a uniform time rate; a time member mounted for rotation about a given axis; a stop

element secured to and movable with said time member and capable of occupying chronological positions therewith; clock-driving means connecting said motor and time member for normally driving the latter at a uniform time-keeping rate; a clock-advancing member adjacent said time member rotatable about the same axis as the latter; a one-way coupling comprising a first coacting part secured to and rotatable with said time member and a second coacting part secured to and rotatable with said clock-advancing member, said coupling parts being movable in approximately the same circular path and being constructed so that said first part may move clockwise past said second part without affecting the condition of relative movement of said members and so that said second part, when moving clockwise at a faster rate than said first part and upon overtaking said first part, engages and drives said first part and time member at the rate of said clock-advancing member; releasable means normally holding said clock-advancing member stationary in a predetermined angular position; signal-responsive means adapted to be operated by a signal transmitted at a predetermined instant with reference to standard time for rendering said holding means inoperative; motion-transmitting means including clutch mechanism operable under the control of said signal-responsive means to connect said motor and said clock-advancing member to rotate the latter from its said angular position for a predetermined angular distance and then to disconnect said clock-advancing member from said motor, said motion-transmitting means being operable when said clutch mechanism is effective and when said time member is at a chronological position later than standard time to cause clock-advancing member to move through its predetermined angular distance at a rate sufficient for said second coupling part to overtake and engage said first coupling part and to advance said time member to a chronological position coincident with standard time at the moment said clutch mechanism disconnects said motor and clock-advancing member; a stop member movable from a retracted position out of the path of movement of said stop element to an advanced position wherein it is in said path of movement, said stop member when in its advanced position being adapted to engage said stop element when the latter reaches said coincident chronological position; and means operable simultaneously upon initial movement of said clock-advancing member to move said stop member into its said blocking position and operable upon the completion of movement of said clock-advancing member for its said predetermined distance to move said stop member to its said normal position.

8. In time-keeping apparatus, the combination of a driving motor operable at a uniform time rate; a rotatable seconds member; means operatively connecting said motor and seconds member for driving the latter at its normal time-keeping rate; a seconds stop element secured to and rotatable with said seconds member; a rotatable minutes member; a minutes stop element secured to and rotatable with said minutes member and occupying chronological positions therewith; driving means connecting said seconds and said minutes member for rotating the latter at its normal time-keeping rate; a clock-advancing member mounted for rotation about the same axis as said minutes member and positioned

alongside thereof in close proximity thereto; releasable means normally holding said clock-advancing member stationary in a predetermined angular position; a one-way coupling comprising a first coating part secured to and rotatable with the minutes member and a second coating part secured to and rotatable with said clock-advancing member, said coupling parts being movable in substantially the same circular path and being so constructed that said first part may move clockwise at its normal time-keeping rate past said second part without affecting the condition of relative movement of said minutes member and clock-advancing member and so that said second part, when moving clockwise at a rate faster than said first part and upon overtaking the latter, engages and drives said first part and consequently the minutes member at the speed of said clock-advancing member; signal-responsive means adapted to be operated by a signal transmitted at a predetermined instant with reference to standard time for rendering said holding means inoperative; motion-transmitting means including clutch means operable under the control of said signal-responsive means and effective to provide a driving connection between said motor and said clock-advancing member so as to rotate the latter from its said angular position for a predetermined angular distance and thereafter being effective to disconnect said motor and clock-advancing member, said motion-transmitting means being operable when the clock-advancing member is rotated throughout the predetermined angular distance and when said minutes member is slow with respect to standard time, to effect driving engagement of said second and first coupling parts and to advance the minutes member to an even hourly position coincident with standard time at the moment said clutch means disconnects the clock-advancing member and motor; a seconds stop member normally occupying an ineffective position and movable to a blocking position where it is engaged by and stops said seconds stop element at an even minute position; a minutes stop member normally occupying an ineffective position and movable to a blocking position where it is engaged by and stops said minutes stop element at said even hourly position; and means operable upon movement of said clock-advancing member from its said position to move both said seconds and said minutes members to their said blocking positions and operable upon said clock-advancing member reaching the end of its movement to move both said stop members back to their said normal positions and thereby release simultaneously said seconds member and said minutes member.

9. In time-keeping apparatus, the combination of a driving motor operable at a uniform time rate; a rotatable seconds member; means operatively connecting said motor and seconds member for driving the latter at its normal time-keeping rate and a seconds stop element secured to and rotatable with said seconds member; a rotatable minutes member; driving means connecting said motor and said minutes member for rotating the latter at its normal time-keeping rate; a clock-advancing member mounted for rotation about the same axis as said minutes member and positioned alongside thereof in close proximity thereto; releasable means normally holding said clock-advancing member stationary in a predetermined angular position; a one-way coupling comprising a first coating part se-

cured to and rotatable with the minutes member and a second coating part secured to and rotatable with said clock-advancing member, said coating parts being movable in substantially the same circular path and being so constructed that said first part may move clockwise past said second part without affecting the condition of relative movement of said minutes member and clock-advancing member and so that said second part, when moving clockwise at a rate faster than said first part and upon overtaking the latter, engages and drives said first part and consequently the minutes member at the speed of said clock-advancing member; signal-responsive means adapted to be operated by a signal transmitted at a predetermined instant with reference to standard time for rendering said holding means inoperative; motion-transmitting means including clutch means operable under the control of said signal-responsive means and effective to provide a driving connection between said motor and said clock-advancing member so as to rotate the latter from its said angular position for a predetermined angular distance and then being effective to disconnect said motor and clock-advancing member, and the motion-transmitting means being operable when the clock-advancing member is rotated throughout the predetermined angular distance and when the minutes member is slow with respect to standard time, to effect driving engagement of said second and first coating parts and to advance the minutes member to a chronological position coincident with standard time at the moment said clutch means disconnects the clock-advancing member and motor; a second stop member normally occupying an ineffective position and movable to a blocking position where it is engaged by and stops said seconds stop element at an even minute position; and means responsive to movement of said clock-advancing member away from its said angular position for moving said seconds stop member to its said blocking position and responsive to said clock-advancing member reaching the end of its movement for moving said stop member back to normal position and thereby releasing said seconds stop element and member.

10. In time-keeping apparatus, the combination of a seconds shaft; a seconds indicating member secured to said shaft for rotation therewith; a clock driving gear mounted on said shaft; a frictional driving connection between said gear and shaft; a driving motor; means operatively connecting the driving motor and gear for driving the latter at a uniform time rate; a minutes sleeve journaled on said shaft; a minutes indicating member and a minutes gear secured to said minutes sleeve and rotatable therewith; a clock driving train connecting said driving gear and said minutes gear for rotating the latter at its normal time-keeping rate; a clock-advancing member mounted for rotation about the same axis as said minutes gear and positioned alongside thereof; releasable means normally holding said clock-advancing member stationary in a predetermined angular position; a one-way coupling comprising a first coating part secured to and rotatable with the minutes gear and a second coating part secured to and rotatable with said clock-advancing member, said coupling parts being movable in substantially the same circular path and being so constructed that said first part can move clockwise past said second part without affecting the condition of relative move-

ment of said gear and member and so that said second part, when moving clockwise at a faster rate than said first part and upon overtaking the latter, engages and drives said first part and minutes gear at the speed of said clock-advancing member; signal-responsive means adapted to be operated by a signal transmitted at a predetermined instant with reference to standard time for rendering said holding means inoperative; motion-transmitting means including clutch means operable under the control of said signal responsive means and effective to provide a driving connection between said clock driving gear and said clock-advancing member so as to rotate the latter from its said angular position for a predetermined angular distance and then being effective to disconnect said driving gear and clock-advancing member, said motion-transmitting means being operable when the clock-advancing member is rotated throughout a predetermined angular distance to effect driving engagement of said second and first coupling parts and to advance the minutes gear and sleeve to a chronological position coincident with standard time at the moment the clutch means disconnects the clock-advancing member and driving gear.

11. Time-keeping apparatus as set forth in claim 10 including stop means effective upon operation of said clock-advancing member to move into blocking position with respect to the seconds stop element and to move out of such blocking position upon disconnecting of said clock-advancing member and driving gear.

12. In a secondary clock mechanism, a synchronously driven motor adapted to be operated continuously according to chronological time; a rotatable seconds member and a rotatable minutes member mounted for rotation about a common axis; means operatively connecting each of said members and the driving motor in driving relationship for rotating the same at normal time-keeping rates of one R. P. M. and one R. P. H. respectively; a clock-advancing member mounted for rotation about said common axis, disengageable means for connecting said seconds member and clock-advancing member in driving relationship for rotating the latter at the same rate as the former; coupling means between said clock-advancing member and minutes member operable when the latter is at a chronological position slower than standard time for driving said minutes member at the rate of the seconds member and for an angular distance sufficient to advance the minutes member to a chronological position coincident with standard time; a latch member normally maintaining said disengageable means disengaged and maintaining said clock-advancing member stationary at a predetermined angular position, said latch member being operable upon tripping thereof to release said disengageable means, and means for tripping said latch member.

13. In a secondary clock mechanism, a synchronously driven motor adapted to be operated continuously according to chronological time; a rotatable seconds member and a rotatable minutes member mounted for rotation about a common axis; means operatively connecting each of said members and the driving motor in driving relationship for rotating the same at normal time-keeping rates of one R. P. M. and one R. P. H. respectively; a clock-advancing member mounted for rotation about said common axis, disengageable means for connecting said

seconds member and clock-advancing member in driving relationship for rotating the latter at the same rate as the former; coupling means between said clock-advancing member and minutes member operable when the latter is at a chronological position slower than standard time for driving said minutes member at the rate of the seconds member and for an angular distance sufficient to advance the minutes member to a chronological position coincident with standard time; a latch member normally maintaining said disengageable means disengaged and maintaining said clock-advancing member stationary at a predetermined angular position, said latch member being operable upon tripping thereof to release said disengageable means, and means for tripping said latch member, said means comprising an electromagnet adapted to receive an energizing signal at a predetermined hourly instant of time.

14. In a secondary clock mechanism, a synchronously driven motor adapted to be operated continuously according to chronological time; a rotatable seconds member and a rotatable minutes member mounted for rotation about a common axis; means operatively connecting each of said members and the driving motor in driving relationship for rotating the same at their normal time-keeping rates of one R. P. M. and one R. P. H. respectively; the connecting means between said minutes member comprising a friction slip device; a traction wheel mounted on said seconds member for rotation in unison therewith; a clock-advancing member mounted for rotation about the axis of rotation of said minutes and seconds members, an advancing pawl carried by said clock-advancing member; means normally urging said advancing pawl into engagement with said traction wheel whereby said clock-advancing member is driven by said traction wheel and at the same rate of speed as the latter; a latch member having a part positioned in the path of movement of said advancing pawl and adapted to engage the latter and maintain the same disengaged from said traction wheel; coupling means between said clock-advancing member and minutes member operable upon engagement of the clock-advancing member by said advancing pawl for driving said minutes member at the rate of the clock-advancing member and consequently of the seconds member for an angular distance sufficient to advance the minutes member to a chronological position coincident with standard time; and means responsive to a signal transmitted at a predetermined hourly instant of time for moving said latch member out of engagement with said advancing pawl to release the latter and establish the driving connection between said clock-advancing member and traction wheel.

15. In a secondary clock mechanism, a synchronously driven motor adapted to be operated continuously according to chronological time; a rotatable seconds member and a rotatable minutes member mounted for rotation about a common axis; means operatively connecting each of said members and the driving motor in driving relationship for rotating the same at their normal time-keeping rates of one R. P. M. and one R. P. H. respectively; the connecting means between said minutes member comprising a friction slip device; a traction wheel mounted on said seconds member for rotation in unison therewith; a clock-advancing member mounted for rotation about the axis of rotation of said

minutes and seconds members, an advancing pawl carried by said clock-advancing member; means normally urging said advancing pawl into engagement with said traction wheel whereby said clock-advancing member is driven by said traction wheel and at the same rate of speed as the latter; a latch member having a part positioned in the path of movement of said advancing pawl and adapted to engage the latter and maintain the same disengaged from said traction wheel; coupling means between said clock-advancing member and minutes member operable upon engagement of the clock-advancing member by said advancing pawl for driving said minutes member at the rate of the clock-advancing member and consequently of the seconds member for an angular distance sufficient to advance the minutes member to a chronological position coincident with standard time; and means for moving said latch member out of engagement with said advancing pawl to release the latter and establish the driving connection between said clock-advancing member and traction wheel, said means comprising a finger carried by said latch member; a trip member having a shoulder thereon designed for engagement with said finger to cause release of said advancing pawl by said latch member; means normally urging said trip member to a position wherein said shoulder is out of engagement with said finger and said latch member is in its operative position; an electromagnet having an armature connected to said trip member, said armature being operable upon energization of said electromagnet to move said trip member to a position in registry with said finger and also being operable upon deenergization of the electromagnet to permit said urging means to move said trip member to its normal position and in so moving cause said finger to be engaged by said shoulder to release said latch member.

16. In a secondary clock mechanism a synchronously driven motor adapted to be operated continuously according to chronological time; a rotatable seconds member and a rotatable minutes member mounted for rotation about a common axis; means operatively connecting each of said members and the driving motor in driving relationship for rotating the same at their normal time-keeping rates of one R. P. M. and one R. P. H. respectively; the connecting means between said minutes member and the motor being a friction slip device; a traction wheel mounted on said seconds member for rotation in unison therewith; a clock-advancing member mounted for rotation about the axis of rotation of said minutes and seconds members, an advancing pawl

carried by said clock-advancing member; means normally urging said advancing pawl into engagement with said traction wheel whereby said clock-advancing member is driven by said traction wheel and at the same rate of speed as the latter; a latch member having a part positioned in the path of movement of said advancing pawl and adapted to engage the latter and maintain the same disengaged from said traction wheel; coupling means between said clock-advancing member and minutes member operable upon engagement of the clock-advancing member by said advancing pawl for driving said minutes member at the rate of the clock-advancing member and consequently of the seconds member for an angular distance sufficient to advance the minutes member to a chronological position coincident with standard time; means for moving said latch member out of engagement with said advancing pawl to release the latter and establish the driving connection between said clock-advancing member and traction wheel, said means comprising a finger carried by said latch member; a trip member having a shoulder thereon designed for engagement with said finger to cause release of said advancing pawl by said latch member; means normally urging said trip member to a position wherein said shoulder is out of engagement with said finger and said latch member is in its operative position; an electromagnet having an armature connected to said trip member, said armature being operable upon energization of said electromagnet to move said trip member to a position in registry with said finger and also being operable upon deenergization of the electromagnet to permit said urging means to move said trip member to its normal position and in so moving cause said finger to be engaged by said shoulder to release said latch member; and cam means operable upon deenergization of said electromagnet for moving said trip member and shoulder out of engagement with said finger to permit said latch member to be moved to its normal operative position.
